UNITED STATES PATENT OFFICE

RICHARD J. KELLY, OF SYRACUSE, NEW YORK.

WICK-RAISING DEVICE FOR LANTERNS.

996,488.

Specification of Letters Patent. Patented June 27, 1911.

Application filed May 12, 1909. Serial No. 495,478.

To all whom it may concern:

Be it known that I, RICHARD J. KELLY, a citizen of the United States, and resident of Syracuse, in the county of Onondaga, in the 5 State of New York, have invented new and useful Improvements in Wick-Raising Devices for Lanterns, of which the following, taken in connection with the accompanying drawings, is a full, clear, and exact description.

The object of this invention is to provide a lantern with simple and effectual means for raising and lowering the wick without the necessity of lifting the globe thereof.

15 To that end the invention consists essentially in the combination with a stationary oil-pot and burner supported thereon, of a wick-moving spindle passing through the burner and having one end projecting there-

20 from, a pinion secured to said projecting end, a circular rack mounted rotatably on the top of the oil-pot and engaging said pinion, and rack-rotating means including an operating member disposed below the oil-

25 pot. The invention also consists in certain novel details of the construction and arrangement of the component parts of the mechanism for turning the wick-raising 30 spindle as will be hereinafter fully described and set forth in the claims.

In the accompanying drawings Figure 1 is a vertical sectional view of the lower portion of a lantern equipped with my wick-raising device; Fig. 2 is an enlarged detail vertical section view showing the shaft and pinion for operating the gear which is disposed concentric with the rack and is connected thereto, and also showing the means 35 for turning said shaft and for throwing the pinion thereof into and out of mesh with the gear; Fig. 3 is a detail plan view of the burner and attached ring formed with the circular rack; Fig. 4 is a transverse sectional 40 view on the line $\alpha-\alpha$ in Fig. 1; and Fig. 5 is a detail view showing the preferred construction of the thumb-piece for turning the vertical shaft and for drawing the same down to throw the pinion out of mesh with 45 the gear.

In the drawings I have illustrated the well known so-called open-bottom lantern comprising the collar or ring 1 to which is secured the usual wire guard or frame 2 —

and base consisting of wires 3 — 3 — and 55 ring 4 .

5 — denotes the globe which is seated on the top of the collar 1 — in the usual manner.

6 — denotes the oil-pot which is disposed concentrically within the collar and provided with an outwardly extending circumferential flange 7 — at its bottom which flange is formed with an upwardly projecting rim 8 — embracing the lower 65 portion of the collar 1 —.

Any of the well known devices may be employed for securing the oil-pot detachably in the collar. To the top of the said oil-pot is applied the usual burner 9 — 70 which may be attached in any suitable manner which will permit it to be conveniently removed.

10 — represents the wick which passes through the usual flattened upright tube 75 11 — of the burner.

In the present instance I have shown the opening of the oil-pot having a bushing 12 — which is soldered or otherwise secured therein. Said bushing is formed with 80 a top flange 12^* — seated at the edge of the opening and is screw-threaded internally to receive a threaded nipple 13 — fastened to the burner, said nipple being formed with an external peripheral flange 14 — bearing upon the flange 12^* — of the bushing. The construction of this burner is immaterial to the present invention, however, I prefer to use that illustrated to afford a convenient application of my wick-raising device which will now be described. 85

15 — denotes the usual shaft which extends transversely through the burner for moving the wick. To the projecting end of said shaft is secured a pinion 16 — which 95 meshes with a circular rack 17 — supported rotatably below the pinion and disposed concentric with the oil-pot. This rack consists of a flat sheet metal ring provided with uniformly spaced radial slots 100 serving as teeth to engage the pinion as more clearly shown in Fig. 3. To the said circular rack 17 — is fastened an internal gear 18 — which rotates the same. This gear is formed preferably from a transversely corrugated sheet metal strip bent into the shape of a ring and is soldered or otherwise secured to the inner face of a 105

downwardly projecting peripheral flange —19— on the flat metal ring on which the rack is formed. To rotatably support this flat ring I clamp its inner edge portion 5 loosely between the burner —9— and the flange —14— on the nipple —13— as shown in Fig. 1.

Extending vertically through the oil-pot —6— is a rotatable shaft —20— which projects through the top and bottom thereof. 10 To the upper end of said shaft is secured a pinion —21— which meshes with the internal gear —18—, and to the lower end of the shaft is attached a thumb-piece —22— 15 for turning the same. This vertical shaft is adapted to be raised and lowered to permit the pinion —21— to be moved into and out of engagement with the gear —18—. It is obvious that when the pinion and gear are 20 out of mesh the wick will not be moved in the operation of unscrewing the burner. The pinion is held in mesh by means of a spiral-spring —23— disposed between said pinion and top of the oil-pot for forcing the 25 shaft upward, by which action of the spring the thumb-piece —22— is caused to bear against the bottom of the oil-pot. The said thumb-piece consists preferably of a sheet metal plate which is of rectangular shape 30 and is pivotally connected to the lower end of the shaft —20— as indicated at —24—.

When the pinion is in mesh with the internal gear the plate —22— presents one of its longitudinal edges to the bottom of the oil-pot as more clearly shown by full lines in 35 Fig. 2. By making the plate in the described shape it acts as a cam when turned to present one of its ends to the bottom of the oil-pot whereby the shaft —20— is drawn 40 down to shift the pinion —21— out of mesh with the said internal gear —18— for the purpose stated. I desire to employ a folded metal plate for this thumb-piece and provide the lower end of the shaft —20— with an enlargement formed with an eye and inserted 45 in the fold of the plate, through which fold and intervening eye portion passes a pivot-pin —25— as illustrated in Fig. 5.

It is obvious that when the thumb-piece is 50 turned to relieve the spring from compression, the said spring will automatically force the shaft upward.

What I claim is:

1. In a lantern, the combination with the 55 oil-pot and the burner, of a wick-raising device comprising a shaft extending transversely through the burner, a pinion secured to said shaft, a rotatable circular rack encircling the burner and engaging the pinion, a rotary shaft supported by the oil-pot, a suitably supported gear actuated by the latter shaft for transmitting motion to the rack, and means for turning said latter shaft as set forth.

65 2. In a lantern, the combination with the

burner, and the wick-raising shaft passing therethrough, of a pinion secured to said shaft, a ring supported rotatably on the burner and provided with a circular rack for actuating said pinion and provided with 70 an internal gear below the rack, a pinion supported on the oil-pot and engaging said gear, and means for actuating the latter pinion as set forth.

3. In a lantern, the combination with a 75 stationary oil-pot and the detachable burner thereon provided with a wick-raising shaft, of a pinion secured to said shaft, and a circular rack secured rotatably to the burner for actuating the pinion and removable with 80 the burner, and means supported on the oil-pot for rotating said rack as set forth.

4. In a lantern, the combination with a 85 stationary oil-pot, the burner, and wick-raising shaft, of a pinion secured to said shaft, a circular rack engaging the pinion, a gear fastened to the rack and disposed concentric therewith, a suitably supported vertical rotary shaft by the oil-pot, a second pinion secured to the upper end of the vertical shaft and meshing with said gear, and a thumb-piece secured to the lower end of said vertical shaft for turning the same as set forth.

5. In a lantern, the combination with a 95 stationary oil-pot, the burner, and wick-raising shaft, of a pinion secured to said shaft, a circular rack supported rotatably above the oil-pot for actuating said pinion, an internal gear fastened to and disposed concentric with the rack, a rotary shaft extending vertically through the oil-pot, a pinion secured to the upper end of the vertical shaft and meshing with the internal gear, and means on the lower end of the vertical shaft 100 105 for turning the latter shaft as set forth.

6. In a lantern, the combination with the wick-raising shaft, of mechanism for turning the same comprising a pinion secured to the shaft, a circular rack engaging said pinion, an internal gear secured to and disposed concentric with the rack, a pinion meshing with the internal gear, and means for actuating the latter pinion and for throwing the same into and out of mesh as and for the 115 purpose set forth.

7. In a lantern, the combination with a 120 stationary oil-pot the burner thereon and wick-raising shaft, of a pinion secured to said shaft, a circular rack supported rotatably above the oil-pot for engaging said pinion, an internal gear secured to the rack, a rotary shaft extending vertically through the oil-pot and adapted to be raised and lowered, a pinion secured to the upper end 125 of the vertical shaft for actuating said gear, a thumb-piece attached to the lower end of the said vertical shaft and bearing against the bottom of the oil-pot and operative for turning the shaft and for drawing the shaft 130

down to throw and hold the pinion thereof out of mesh with the gear, and a spiral-spring disposed between the pinion and top of the oil-pot for throwing the pinion into mesh with the gear as set forth.

8. In a lantern, the combination with a stationary oil-pot, the burner and wick-raising shaft, of a pinion secured to said shaft, a flat ring supported rotatably and concentrically above the oil-pot and provided with a rack engaging said pinion and formed with a downwardly projecting circumferential flange, an internal gear on said flange, a

rotary shaft extending vertically through the oil-pot and having its ends projecting 15 from the top and bottom thereof, a pinion secured to the upper end of the vertical shaft and meshing with the said internal gear, and a thumb-piece attached to the lower end of said vertical shaft for turning the same as 20 set forth.

RICHARD J. KELLY.
